DESIGN FOR A COMBINED DOLL AND PARACHUTE

Marion Hoyle, Pasadena, Calif.

Application November 26, 1945, Serial No. 124,090

Term of patent 14 years

(Cl. D34—4)

To all whom it may concern:

Be it known that I, Marion Hoyle, a citizen of the United States of America, a resident of Pasadena, California, in the county of Los Angeles, State of California, have invented a new, original, and ornamental Design for a Combined Doll and Parachute, of which the following is a specification, reference being had to the accompanying drawing, forming part thereof.

Fig. 1 is a front perspective view of a combined doll and parachute, showing my new design; and Fig. 2 is a rear perspective view thereof.

I claim:

The ornamental design for a combined doll and parachute, as shown.

MARION HOYLE.
